UNITED STATES PATENT OFFICE.

GERALDINE O'BRIEN COOK, OF BOSTON, MASSACHUSETTS.

DESIGN FOR AN UNDERGARMENT-BODY.

SPECIFICATION forming part of Design No. 29,912, dated December 27, 1898.

Application filed November 14, 1898. Serial No. 696,467. Term of patent 14 years.

To all whom it may concern:

Be it known that I, GERALDINE O'BRIEN COOK, a citizen of the United States, residing at Boston, in the county of Suffolk and State 5 of Massachusetts, have invented and produced a new and useful Design for an Undergarment-Body, of which the following is a description, reference being had to the accompanying drawing, forming a part thereof.

10 The drawing shows an undergarment illustrating my design.

The leading feature of my design comprises an undergarment, the plain body of which is provided in front with short distinctive ornamental ribs below the neck at each side of and parallel to the front opening of the body.

15 In the drawing the plain body A' of the undergarment A is provided in front with

short distinctive heavy ornamental ribs a^x below the neck a' at each side of and parallel 20 to the front opening a^2 of the body, the ribs presenting a very distinct and ornamental effect to the eye compared with the plain flat surface of the adjacent portions of the garment.

25 Having fully described my design, what I claim is—

The design for an undergarment-body, substantially as shown and described.

In testimony whereof I have signed my 30 name to this specification in the presence of two subscribing witnesses.

GERALDINE O'BRIEN COOK.

Witnesses:

JOHN C. EDWARDS,
AUGUSTA E. DEAN.
